UNITED STATES PATENT OFFICE.

JOHN H. JEFFRIES, OF INGLEWOOD, AND EDWARD M. DOHERTY, OF LOS ANGELES, CALIFORNIA.

PUMP.

Application filed January 29, 1923. Serial No. 615,631.

To all whom it may concern:

Be it known that we, JOHN H. JEFFRIES and EDWARD M. DOHERTY, citizens of the United States, residing in Inglewood and Los Angeles, respectively, in the county of Los Angeles and State of California, have invented a certain new and useful Pump, of which the following is a specification.

This invention relates to that type of pump that is employed in wells for pumping oil or water, and an object, in general, of the invention is to provide a pump that operates in a superior manner.

Another object is to provide for deflection from axial alinement of the plunger-operating stem and plunger so that lateral motion of the sucker line will not tend to deflect the plunger. Thus the plunger is self-aligning so that it will wear evenly from end to end and will not wear the working barrel unduly at any particular point.

Another object is to provide a novel construction that permits of relative lateral oscillation or deflection of the plunger and sucker line.

Another object is to provide for relative lateral oscillation of the plungers of a double acting pump.

Another object is to provide for effectual packing of the joint between the valve and the member on which it reciprocates.

A further object is to minimize the entrance of sand between the pump plunger and working barrel.

Another object is to guard against the entrance of sand to the universal joint.

The accompanying drawings illustrate the invention:

Figure 1 is an elevation, partly in section, of a pump constructed in accordance with the provisions of this invention, said pump having a plurality of plungers.

Fig. 2 is an enlarged sectional detail of the joint between the lower plunger stem and the sucker line that operates it.

Fig. 3 is a sectional elevation of one of the plungers and its associated parts.

Figs. 4, 5 and 6 are plan sections on the lines indicated by 4-4, 5-5 and 6-6, respectively, Fig. 3.

The working barrel of the pump is indicated at 11 and may be provided with a single valved plunger or with a plurality of valved plungers, according as the pump is

of the single plunger type or double acting. In this particular instance, in Fig. 1, two plungers are shown and are indicated at 12. Since the plungers are alike a description of one will suffice for both. Each plunger is provided with a valve seat 13 on its inner face adapted to be engaged by a valve plug 14 on a sleeve 15. Other valve means may be used in place of those shown and described. The sleeve 15 is guided and reciprocates upon a tubular member 16 which, in this instance, is integral with the plunger. The tubular member 16 is connected by radiating webs 17 to the lower section 18 of the plunger, said section 18 being provided with the valve seat 13 and being screw threaded at 19 into the upper plunger section 20. The webs 17 are slightly below the level of the sleeve 15, when the valve 14 is closed, so as not to interfere with the operation of said valve.

The bore of the sleeve 15 is slightly enlarged at its upper end as indicated at 21, and said enlargement terminates downwardly at an internal shoulder 22. When the valve 14 is closed, the upper end of the tubular member 16 is substantially flush with the shoulder 22 and seated on said end and shoulder is a resilient packer 23 of rubber or other suitable material. The bore portion 21 is provided at its lower end with an annular groove 24 which communicates with an outwardly and downwardly slanting duct 25 in the sleeve 15.

Engaging the upper end of the sleeve 15 is an annular cap 26 formed by a flange on the lower end of a tubular member 27. The cap 26 is held toward the sleeve 15 by a coil spring 28 that surrounds a tubular fluid-deflecting shield 29 extending downwardly from an upper spring seat 30 with which the upper end of the spring 28 engages. Thus the spring 28 aids in quickly closing the valve at the beginning of the up stroke of the plunger. The shield 29 is interposed between the spring 28 and the tubular member 27.

The spring seat 30 is suitably connected with a plunger-operating stem 33. In this instance the spring seat 30 bears against a tubular spacing member 43 which in turn bears against a coupling member 31 that is provided with internal screw threads 32 for connection with a sucker line, not shown.

The stem 33, which may be tubular as shown, is threaded at its upper end into the coupling member 31 and extends through the tubular members 27, 43 and also into the tubular member 16.

The stem 33 is connected with the tubular member 16 by a universal or flexible joint, indicated in general by the character 34. The universal joints are hollow and, though 10 different constructions may be employed for the universal joint 34, I have illustrated a preferred construction as follows: The tubular member 16 is provided with an internal annular concave seat 35 in which is seated the male member 36 of the joint. In this instance, the member 36 constitutes a nut which is screw threaded on to the lower end 15 of the stem 33. The members 16, 36 thus constitute a bearing which permits of universal motion between said members. The lower end of the member 36 is provided with a concave seat 37 against which fits an annular flange 38 of a thimble 39. Loosely surrounding the thimble 39 is a nut 40 which is 20 screw-threaded into the enlarged lower end 41 of the tubular member 16, that constitutes a fluid-deflecting shield for the universal joint. Clamped between the nut 40 and thimble 39 is a resilient cushion 42 of rubber 25 or the like. The nut 40 fits loosely on the thimble 39 so as to permit relative motion therebetween when the members 16, 33 are relatively oscillated sideways. The cushion 42, though readily yielding under such 30 motion, holds the flange 38 in close engagement with the seat 37 and the member 36 in close engagement with its seat 35, thus preventing the entrance of sand which would 35 tend to cut said seats.

The upper end of each plunger is beveled inwardly and downwardly, as indicated at 40, the bevel terminating at the periphery of the plunger in a feather edge so as to deflect any sand, that may be in the liquid being pumped, into the plunger and thus prevent the sand from penetrating between the plunger and working barrel and cutting them. In order to dispose of any grains of sand that may pass between the upper end 45 of the plunger and the working barrel, an annular groove 45 is provided adjacent the upper end of the plunger and a duct or ducts 46 lead aslant downwardly and inwardly from the groove 45 to the interior of the plunger. It is to be noted that the upper 50 end of the plunger is a substantial distance above the valve so as to hold a considerable amount of sand that may settle out of the liquid above the valve during the upstroke 55 of the plunger, thus insuring that such sand will not get between the plunger and working barrel.

The pump operates as follows: Assuming that the lower plunger is beginning 60 its down stroke and that the upper plun-

ger is beginning its up stroke, the lower valve will open to allow the liquid to pass into the working barrel above the lower plunger, and the upper valve will close so as to lift the column of liquid above said upper valve. As the plungers are reciprocated, in a manner well understood in the pumping art, any lateral deflection or whipping of the sucker lines, not shown, will take place without tending to force the plungers, 70 against any particular zone of the working barrel, because of the provision of the universal joints. Also, if the working barrel should not be perfectly straight, the plungers will independently aline themselves in 75 the working barrel to follow out any bend that there may be in said working barrel.

When the plunger starts on its down stroke its valve will be raised against the pressure of the spring 28 and the liquid column above said valve so that the liquid below the valve can rush into the space in the upper portion of the plunger to fill the partial vacuum created by the descending plunger. As the column of liquid ascends into 80 the plunger, the shield 41 deflects the liquid and any sand that there may be therein away from the universal joint so that said sand will not penetrate between the members 16, 36 and the members 36, 39. As the liquid column follows upwardly through the plunger in the space above the valve, the shield 29 will protect the upper end of the tubular member 27 against the entrance of sand between 85 said tubular member and the stem 33, thus tending to prevent penetration of the sand to the packer 23 and to the seat 35 through the space between the members 27, 16 and the stem 33. If, perchance, any grains of sand should penetrate into the enlarged bore 90 portion 21, in which the packer 23 is positioned, said grains will lodge in the groove 24 and then pass by way of the duct 25 into 95 the plunger.

In Figure 2 is disclosed a detail of the 100 construction for connecting the lower plunger with the sucker line, indicated at 47. In this instance the sucker line 47 is screw-threaded at 48 into a plug 49 which, in turn, is screw threaded into the lower coupling 31. 105 It will be clear from this that the plungers are of identical construction and that the sucker line 47 passes through the tubular stem 33, which will be operated by another sucker line, not shown, surrounding the sucker line 110 47, in a well known manner.

The lower section 18 of each plunger is provided at its lower end with a portion 50 which is spaced sufficiently from the working barrel to form between the portion 50 115 and the working barrel a dead liquid space α so that the liquid trapped in said space, on the down stroke of the plunger, will act as a cushion or barrier to prevent the entrance of sand to such space, thus insuring against 120 125 130

the sand getting between the plunger and working barrel and cutting and wearing them, as the plunger descends.

We claim:

- 5 1. In a pump, the combination of a working barrel, a tubular plunger in the working barrel, a valve seat on the inner face of the plunger, a tubular member inside of the plunger and spaced therefrom and connected therewith by a flexible joint, and a sleeve slidably fitting on the tubular member and provided on its periphery with a valve to close onto said seat. 65

10 2. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, a second tubular member inside of the first tubular member, and a flexible joint connecting one end of the first and second tubular members. 70

15 3. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, a second tubular member inside of the first tubular member, and a flexible joint connecting one end of the first and second tubular members. 75

20 4. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, a second tubular member inside of the first tubular member, and a flexible joint connecting one end of the first and second tubular members. 80

25 5. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, the sleeve bore being enlarged at one end, a packer in the enlarged bore covering the joint between the sleeve and the tubular member when the valve is closed, a second tubular member engaging one end of the sleeve, a third tubular member outside of the first and second tubular members, a spring seat connected with the third tubular member, and a spring between the seat and sleeve, the spring seat having a fluid deflecting shield extending below the level of the upper end of the second tubular member. 85

30 6. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, the sleeve bore being enlarged at one end, a packer in the enlarged bore covering the joint between the sleeve and the tubular member when the valve is closed, a second tubular member engaging one end of the sleeve, a third tubular member outside of the first and second tubular members, a spring seat connected with the third tubular member, and a spring between the seat and sleeve, the spring seat having a fluid deflecting shield extending below the level of the upper end of the second tubular member. 90

35 7. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, the sleeve bore being enlarged at one end, a packer in the enlarged bore covering the joint between the sleeve and the tubular member when the valve is closed, a second tubular member engaging one end of the sleeve, a third tubular member outside of the first and second tubular members, a spring seat connected with the third tubular member, and a spring between the seat and sleeve, the spring seat having a fluid deflecting shield extending below the level of the upper end of the second tubular member. 95

40 8. In a pump, the combination of a working barrel, a tubular plunger in the working barrel, a valve seat in the plunger, an operating stem for the plunger, a tubular member connected with the plunger, a flexible joint connecting the operating stem with the tubular member, a portion of said tubular member forming a fluid-deflecting shield around the flexible joint, and a valve to close onto the valve seat. 100

45 9. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, the sleeve bore being enlarged at one end, a packer in the enlarged bore covering the joint between the sleeve and the tubular member when the valve is closed, a second tubular member engaging one end of the sleeve, a third tubular member outside of the first and second tubular members, a spring seat connected with the third tubular member, and a spring between the seat and sleeve, the spring seat having a fluid deflecting shield extending below the level of the upper end of the second tubular member. 105

50 10. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, the sleeve bore being enlarged at one end, a packer in the enlarged bore covering the joint between the sleeve and the tubular member when the valve is closed, a second tubular member engaging one end of the sleeve, a third tubular member outside of the first and second tubular members, a spring seat connected with the third tubular member, and a spring between the seat and sleeve, the spring seat having a fluid deflecting shield extending below the level of the upper end of the second tubular member. 110

55 11. In a pump, the combination of a working barrel, a tubular plunger in the working barrel, a valve seat on the inner face of the plunger, a tubular member inside of the plunger and spaced therefrom and connected therewith, a sleeve slidably fitting on the tubular member and provided on its periphery with a valve to close onto said seat, the sleeve bore being enlarged at one end, a packer in the enlarged bore covering the joint between the sleeve and the tubular member when the valve is closed, a second tubular member engaging one end of the sleeve, a third tubular member outside of the first and second tubular members, a spring seat connected with the third tubular member, and a spring between the seat and sleeve, the spring seat having a fluid deflecting shield extending below the level of the upper end of the second tubular member. 115
